UNITED STATES PATENT OFFICE.

HAROLD EDWARD SHERWIN HOLT, OF FARNBOROUGH, ENGLAND.

FLARE FOR USE ON AIRCRAFT.

1,360,527.

Specification of Letters Patent. Patented Nov. 30, 1920.

Application filed April 23, 1917. Serial No. 163,958.

To all whom it may concern:

Be it known that I, HAROLD EDWARD SHERWIN HOLT, a subject of the King of Great Britain and Ireland, residing at The Grange, 5 Farnborough, Hampshire, England, have invented certain new and useful Improvements in Flares for Use on Aircraft, of which the following is a specification.

This invention for improvements in flares or illuminating bodies for use on aircraft relates to flares or illuminating bodies employed to facilitate the landing of aeroplanes at night and comprising a cylindrical or similar casing containing combustible 15 material, suspended from a convenient part of the aeroplane and provided with igniting means under the control of the airman.

One object of this invention is to provide a flare of this type which after being first 20 ignited and burning for a time shall be automatically extinguished, and still be capable of being re-ignited and burning for a further period so that, if the landing place first examined with the aid of the flare is found to 25 be unsuitable, there will still be an unconsumed portion or portions available for further use.

Another object of this invention is to conserve the flare material, especially in long 30 burning flares, where the material, owing to the heat of combustion at the lower or burning end, tends to disintegrate and fall away.

The first object of the invention is attained by isolating two or more portions of 35 the flare material from each other so that one portion can burn away without igniting another, the separate portions of flare material being either contained in different compartments of the same casing or in separate casings, and providing separate igniting means for the different flare portions preferably controlled from the same switch.

In a practical form of the invention as applied to a twice-acting flare or a flare for 45 affording two separate periods of illumination, two portions of flare material are contained in the same casing one above another but are separated by spaced disks of wood and cardboard having an air space between 50 them or by a solid block of wood or other non-conductor of heat. The lower portion burns away first without igniting the upper portion, which is sufficiently insulated from the heat generated by the lower portion by 55 means of the said disks and air space, or other non-conductor.

A battery or other source of electric current with controlling switch is connected with separate igniters for the two portions of the flare, the circuit of the upper portion 60 which is ignited last being controlled by the same switch as the lower portion, but kept open during the first closing of said switch by an auxiliary switch or spring contact arranged to close automatically after the lower 65 portion of the flare has been ignited. For this purpose the spring contact, which is mounted on a wooden disk at the top of the flare, is conveniently held open by a wire, so fixed to the lower portion of the flare, that it 70 is released when the flare begins to burn, and allows the contact to close. A tube for the passage of air may be arranged centrally in the flare material, such tube extending from end to end of the flare casing and burning 75 away with the casing.

Where perforated disks of paper or the like are employed in flares for preventing disintegration of the material by heat as aforesaid, the disks may be loosely inserted 80 or adhesively attached by their edges to the flare casing and are inserted when the flare material is being introduced into the casing.

In the accompanying drawings:

Figure 1 is a longitudinal section of a 85 twice-acting flare constructed according to this invention the section being taken along the line 1—1 Fig. 5 but showing the wiring more or less conventionally for the sake of clearness.

Fig. 2 is an elevation of the same.

Fig. 3 is a transverse section taken at 3—3 Fig. 1.

Figs. 4 and 5 are an elevation and plan respectively of the upper part of the flare. 95

Fig. 6 is a sectional elevation taken at right angles to Fig. 4.

Fig. 7 is a sectional plan, and

Fig. 8 is a diagram of the electrical ignition circuits.

Figs. 9 and 10 are elevation and developed plan respectively showing a modified arrangement including separate flares on the same bracket, and

Fig. 11 is a diagram of the electrical ignition circuits of same.

As shown in Fig. 1 the flare casing *a* is divided into upper and lower compartments *a'* *a''* by spaced disks of wood *b* and cardboard *c* having an air space *d* between them. Each compartment *a'* *a''* is filled with 110 a separate portion of flare material (not

shown) and provided at its lower end with a separate igniter d or d' embedded in priming material e or e' . A cardboard tube f or f' for admitting air to the core of the flare material is arranged centrally of each flare compartment, the lower tube f' being fixed at its upper end in the wooden disk b while the upper tube f is likewise fixed in a wooden closing plug g inserted and 10 fixed in the top of the flare casing a .

An automatic auxiliary switch consisting of a metal tongue h is arranged in the plug g and pressed toward a contact pin i by a bent wire spring h' , Figs. 6 and 7. The 15 switch tongue h is connected into the igniting circuit of the upper flare compartment a' and is held away from its contact pin i , to keep the circuit open until after the flare material in the lower compartment a^2 has 20 been ignited, by a wire j which runs through a protecting sheathing k on the flare body and is attached as shown to a nail or similar fastener l driven into the lower part of the casing a . It will be seen that as the lower 25 part of the casing is consumed together with the flare material in the lower compartment a^2 the wire will be released automatically permitting the switch tongue h to move into the closed position.

30 As shown in the diagrammatic view, Fig. 8, the igniter d is included in a conductor which comprises conducting wires x and x' , the latter being directly connected to the battery or energizing means n , and a switch 35 m being provided to close the circuit at will of an aviator or operator. A second conductor includes the second igniter d' and also includes conducting wires y and y' . This second conductor is adapted to be put 40 in circuit with the generator or energizing means n through the medium of the switch h , the binding point i being connected with the first described conductor and constituting a contact against which the switch h 45 constantly tends to move; but the wire j , being anchored by the pin b , is normally held open, and therefore, the second described conductor is normally ineffective or 50 inoperable to immediately energize the igniter d , and it remains inoperable or ineffective until the portion of flare material first 55 ignited has released the anchor l , whereupon the switch m is automatically closed and immediately effects ignition, by means of the igniter d' in the event that the switch m remains closed, or upon closing this 60 switch.

The circuit wires x x' and y y' may be 65 arranged in any convenient manner on the flare body. As shown both the wires x x' for example leading to the igniter d pass down the outside of the flare body but within the outer covering thereof one being continued in that manner to the bottom end 70 of the flare body while the other is led into

and through the tube f' . At the upper end one wire x is led through an opening o to the center of the plug g and away to the switch m while the other x' is also led to the center of the plug g through the same opening o and thence to the outside again through another hole which terminates near the contact pin i of the automatic switch. At this point, the wire is bared and connected to the contact pin i being then 75 doubled back upon itself and led through the same hole to the center again and away to the terminal of the battery n . Circuit wires y y' pass from the igniter d' up the tube f , the wire y being joined to or led to 80 the same terminal as wire x while the wire y' is connected to the holding nail or screw of the switch tongue h .

In a modified form of construction instead of employing two flare portions in- 85 closed in a casing common to both, separate flares may be arranged on the same bracket or support and their ignition controlled by the same switch in a manner similar to that already described. Such an arrangement is 90 illustrated in Figs. 9 to 11 in which separate flares a^3 a^4 are fitted with terminal plugs inserted in terminal coupling sockets p p' provided on an insulating angular bracket 95 q carried on a cylindrical stock r adapted to be clamped in a suitable suspending bracket. An automatic switch comprising a spring tongue h' and contact piece i' is in this case mounted on the bracket q ; the spring tongue h' being held in the open position by a wire j' attached to the flare a^3 which is to be ignited first. Terming the 100 circuits x x' and y y' as before, it will be seen that on first closing the switch m the circuit x x' which ignites the flare a^3 is completed, after which the automatic switch h' i' is closed so that on again closing switch 105 m the circuit of the igniter in the other flare a^4 will be completed.

What I claim and desire to secure by Letters Patent is:—

1. A flare or illuminating device comprising portions of combustible material isolated from one another, igniting means for each portion, means normally effective to 115 actuate one of the igniting means but normally ineffective to actuate the remaining igniting means, and means controlled upon combustion of the portion first ignited to render effective the actuating means of a 120 previously ineffective igniting means.

2. A flare or illuminating device comprising a plurality of combustible elements, igniting means for each element including electric circuits with battery and switch, a 125 circuit breaking means included in the circuit of the igniting means of one of the elements and adapted to normally render same ineffective, and means dependent upon the combustion of a combustible element with 130

normally effective igniting means for closing the said circuit breaking means to render effective the previously ineffective igniting means.

5. 3. A flare comprising two portions of combustible material, igniting means for each portion, electrically controlled actuating means normally operable to actuate one of these igniting means but normally ineffective to immediately actuate the second igniting means, and means controlled upon combustion of the portion first ignited to render effective the actuating means for effecting ignition by the second igniting means.

10. 4. A flare comprising two combustible portions, an electric conductor, including an igniter in position to ignite only one of said portions when electrically energized, a second electric conductor including a second igniter in position to ignite the second one of said portions when electrically energized, a normally open switch adapted to connect the first and second said conductors, means

25 to electrically energize the first said conductor, and means adapted to become effective upon combustion of the portion first ignited to close said switch and thereby subject the second igniter to the control of the energizing means.

30 5. A flare or illuminating device comprising a plurality of combustible elements; an electric circuit including a switch, a shunt and an igniter extraneous of the shunt and in position to ignite one of said combustible 35 elements, said shunt including an igniter and an automatic circuit closer; and means combining with one of said combustible elements for normally holding said circuit closer open and allowing it to close after 40 the igniter extraneous of said shunt has ignited the correlated combustible element, whereby the circuit through said shunt can cause the igniter in the shunt to ignite another of said combustible elements.

45 In testimony whereof I have affixed my signature.

HAROLD EDWIN SHERWIN HOLT
